UNITED STATES PATENT OFFICE.

JOSEPH ROSEMONT AND FRANK AMATI, OF TRENTON, NEW JERSEY.

WATCH.

1,179,761.

Specification of Letters Patent.

Patented Apr. 18, 1916.

Application filed July 24, 1915. Serial No. 41,749.

To all whom it may concern:

Be it known that we, JOSEPH ROSEMONT and FRANK AMATI, subjects of the King of Italy, residing at Trenton, in the county of 5 Mercer and State of New Jersey, have invented new and useful Improvements in Watches, of which the following is a specification.

This invention relates to certain novel and 10 useful improvements in watches.

In carrying out the present invention it is 15 our purpose to provide a watch wherein the dial may be illuminated conveniently whenever necessary or desired in order to facilitate the reading thereof.

It is also our purpose to provide a watch 20 wherein the lamp, source of energy therefor, and switch controlling the connection between the source of energy and the lamp will be carried by the watch so arranged as 25 to produce a neat and compact article and one wherein the possibility of derangement of component parts will be reduced to a minimum.

With the above recited objects in view and 30 others of a similar nature, the invention consists in the construction, combination, and arrangement of parts set forth in and falling within the scope of the appended claims.

In the accompanying drawing: Figure 1 35 is a face view of a hunting case watch constructed in accordance with the present invention. Fig. 2 is a sectional view through the watch. Fig. 3 is a sectional view. Fig. 4 is a fragmentary sectional view through the watch of the open face type constructed in accordance with our invention.

In accordance with our invention, the case 40 of the watch is slightly increased in diameter and a channel formed therein concentrically of the gear train and disposed within this channel is a battery, while mounted upon the dial of the watch is a lamp and a switch connected in series circuit with the battery. 45 This switch is under the control of the stem of the watch and when the stem is moved inwardly, the switch is closed so that current may flow from the battery through the lamp to energize the latter and illuminate the 50 dial, thereby enabling the dial to be read easily and conveniently under all conditions.

Referring now to the drawing in detail, 55 1 designates a watch of the hunting case type. The case of the watch is slightly increased in diameter to form an annular

chamber or channel 2 arranged concentrically of the case and around the gear train. Disposed within the chamber 2 are dry cells 3, 3 each curved longitudinally to conform to the channel. Suitably secured to the partition between the gear train and the dial of the watch is an electric lamp receptacle 4 carrying a lamp 5 disposed within an opening formed in the dial and adapted to illuminate the dial when energized. Also 60 secured to the division plate carrying the socket or receptacle 4 is a switch 6. In the present instance this switch embodies a base 7 of fiber or other insulating material, a stationary contact 8 secured to the base, and a movable contact finger 9 secured to the base and composed of springy material. This movable contact is normally spaced apart from the stationary contact and is disposed in the path of movement of a pin 10 slidably mounted within an opening 11 65 formed in the flange carrying the dial. Secured to the pin 10 at the inner side of the flange that carries the dial, is a stop nut 12 while fastened to the outer end of the pin 80 beyond said flange is a collar 13 and interposed between the collar 13 and the flange is a coiled expansion spring 14 acting to hold the inner end of the pin normally out of engagement with the spring contact finger 9. In this form of our invention, a disk 15 85 is fixed to the stem of the watch concentrically of said stem in juxtaposition to the outer end of the pin 10. The battery formed of the cells 3, the lamp and the switch are 90 connected in series circuit as clearly illustrated in Fig. 2 of the drawing.

In practice, when it is desired to energize the lamp so as to illuminate the dial, the stem of the watch is forced inwardly and as the stem nears the limit of its inward movement the disk 15 engages the pin 10 and slides the latter against the tension of the spring 14, and in this movement of the pin, the inner end thereof engages the spring contact finger 9 and moves such finger into engagement with the stationary contact 8 thereby closing the circuit and energizing the lamp.

When our invention is installed in a hunting case watch, the stem is preferably capable of sliding movement relatively to the crown, as shown in Figs. 1, 2 and 3 of the drawing, and the disk 15 is so arranged relatively to the outer end of the pin 10, that 105 110

in the initial movement of the stem, the cover will be released, while the pin will remain uninfluenced by the disk. In the continued movement of the stem, succeeding the 5 release of the cover, the crown moves inwardly with the stem and the disk engages the pin to close the switch.

In the construction illustrated in Fig. 4, we have shown the stem and crown fixed 10 to each other and this construction is preferably used in open face watches.

Having described our invention, what is claimed is:

1. A watch including a stem, a dial, a gear 15 train, a plate, and a flange for holding the dial and having the case formed with an annular chamber surrounding the gear train, a battery in said chamber, a lamp carried by the plate between the gear train and the 20 dial and projecting through the dial, a switch on said plate, a pin slidably mounted within the flange carrying the dial of the watch, a disk on the stem of the watch and movable therewith to engage said pin to move the latter into engagement with the 25

switch to close the same, and circuit connections between said battery, lamp, and switch.

2. A watch including a stem, a dial, a gear train, a plate, and a flange for holding the dial and having the case formed with an 30 annular chamber surrounding the gear train, a battery in said chamber, a lamp carried by the plate between the gear train and the dial and projecting through the dial, a switch on said plate, a pin slidably mounted 35 within the flange carrying the dial of the watch, a disk on the stem of the watch and movable therewith to engage said pin to move the latter into engagement with the switch to close the same, circuit connections 40 between said battery, lamp, and switch, and a spring holding said pin normally out of engagement with said switch.

In testimony whereof we affix our signatures in presence of a witness.

JOSEPH ROSEMONT.
FRANK AMATI.
